(57) **CLAIM**

I claim the ornamental design for a folder, as shown and described.

DESCRIPTION

FIG. 1 is a front/right/top perspective view of a first embodiment of the folder (hanging check with gusset);

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and

FIG. 7 is a left side elevational view thereof.

FIG. 8 is a front/right/top perspective view thereof; and,

FIG. 9 is a front elevational view thereof.

The broken lines form no part of the claimed design.

1 Claim, 5 Drawing Sheets
